MATRIX ROLLING MACHINE

Herbert C. Behrens, Battle Creek, Mich., assignor to Duplex Printing Press Company, Battle Creek, Mich., a corporation of Michigan

Application May 14, 1938, Serial No. 208,016

17 Claims. (Cl. 101—12)

This invention relates to matrix rolling machines adapted to press sheets of flong or matrix material against the printing surface of type forms to produce therein an intaglio impression, stereotype plates being subsequently cast from said impressed matrix. Such machines, ordinarily called "mat rollers" usually comprise a reciprocating flat bed on which is placed the chase containing a type form, an upper roller being vertically adjustably mounted above and cooperating with the bed, and a lower roller being placed under the bed along the line of pressure of the upper roller to support the bed under pressure of the upper roller. The flong or matrix material is placed upon the type form with one or more blankets of resilient material such as felt, rubber, or cork disposed thereover.

The upper roller is adjusted to press the blankets downwardly with sufficient force to press the flong or matrix material into the interstices of the type form, making therein a reverse copy of the form. The bed, after making one pressing stroke on the matrix, stops automatically. At the end of such stroke, while the bed is stationary, the mat and form may be removed and the bed may be started on its return stroke. A new sheet of flong may then be placed on the form (or a new form) so that a mat may be made at each stroke of the bed.

This matrix is placed in a casting machine to produce a curved printing plate which has on its outer surface an exact copy of the type form. It is important that these plates if cast from different matrices register with each other, especially when two to four plates are used in the printing press to print on the same page, for obviously the plates used for one color should print in places left blank for another color so that the colors will not overlap in places, or blank spaces will not be left where printing should appear.

It is customary to drive positively the upper roller by gears meshing with either the bed or the lower roller so that the upper roller will revolve with the same peripheral speed and in the same direction as the bed. It has been found in practice that the loose blankets between the upper roller and the matrix at times will creep and cause the matrix to creep on the type form thereby resulting in distortion so that the matrices will not match or register. The stroke of the bed is necessarily longer than the length of the type form and chase, and sufficient length is provided so that the operator can manipulate the flong and blankets before they enter the bite of the upper roller as it revolves. My present invention is an

improvement in the means and method of driving the upper roller in such matrix rolling machines, and consists in driving the upper roller to overcome its inertia as the bed starts its stroke, utilizing the time during which the upper roll is passing over the end of the chase, and then releasing the driving means of said roller to allow same to revolve freely over the form, said upper roller being then driven only by frictional contact of its surface with the blankets while the bed is passing under the roller.

In the accompanying drawings I have illustrated several practical embodiments of the invention, and will describe the same with reference thereto, and will refer to the claims for the essentials of the invention, and novel features of construction, and novel combinations of parts, for which protection is desired.

In said drawings:—

Fig. 1 is a longitudinal section through one form of matrix rolling machine, showing the position assumed by the parts of driving means for the upper roller when the bed is in mid-position.

Fig. 2 is a view similar to Fig. 1 showing the position of the parts of the driving means when the bed is at the outer extremity of one stroke.

Fig. 3 is a transverse section through the center of the machine shown in Figs. 1 and 2.

Fig. 4 is an end elevation showing the driving means applied to a different form of machine.

Fig. 5 is an enlarged elevation showing more in detail the mounting of a friction block in the driving disk.

Fig. 6 is a section on the line 6—6, Fig. 5.

The invention is illustrated in Figs. 1-3 in connection with a hydraulic matrix rolling machine such as shown in a copending application of Thomas H. Mars and Herbert C. Behrens, Serial No. 127,306, filed February 23, 1937, the machine comprising opposite side frames 1 and 2 suitably connected together and in which the bed 4 travels, the length of the frames being slightly greater than the length of the bed 4 plus its length of travel. The bed 4 reciprocates horizontally on track bars 7, 7a (Fig. 3) in the side frames and is supported at the pressure point upon a centrally disposed lower roller 5, disposed beneath an upper roller 6, the lower roller 5 being journaled in bearings 5a, 5b in the side frames, while the upper or presser roller 6 is journaled in bearings 6a (Fig. 3) supported in hangers 8 which are vertically adjustable in guideways (not shown) in the side frames. The shaft of lower roller 5 carries gears 5d at its ends which mesh respectively with 35

racks 4d on the underside of bed 4 adjacent track bars 1, 1a, so that the bed will travel at the same speed as the periphery of roll 5. In said copending application Serial No. 127,306 the bed 4 or roller 5 is driven directly by hydraulic means, comprising cylindric bores 4a in which are mounted stationary pistons 4b dividing the cylinders 4a into right and left chambers 4r and 4l. To the pistons 4b are connected the inner ends 10 of axially aligned tubes 4e, 4f, the outer ends of which are connected to end bars 1x of the frame by couplings 4g. The ends of cylinders 4a are closed by heads 4h provided with stuffing boxes 4i making a close sliding fit on tubes 4l, 4r, and 15 oil or other fluid is alternately pumped into either chamber 4l, 4r through pipes 4j opening into the outer ends of tubes 4e, 4f, each tube having an opening 4k adjacent the piston 4b, so that while fluid is pumped into one chamber, fluid is being 20 exhausted from the other, a suitable valve means (not shown) operated by levers 4m controlling the flow of fluid from a pump and reservoir as disclosed in said application. The cylinders 4a and pistons 4b serve to intermittently reciprocate the bed, and consequently rotate the roll 5 by reason of the racks and pinions 4d, 5d. If desired the roll 5 might be rotated directly as disclosed also in said application in order to intermittently reciprocate the bed 4.

30 In the aforesaid application Serial No. 127,306 the shaft of lower roller 5 adjacent the side frame 2 was provided with a large gear meshing with a gear of same size on the adjacent end of the shaft of upper roller 6, so as to synchronize the peripheral speeds of the said rollers with the movement of bed 4, the rollers rotating in the same direction as the bed. In my improved construction however the said intermeshing gears on rollers 5 and 6 are removed, and in place of 35 said gears the shaft of upper roller 5 is provided with a driven disk 6e, and the shaft of lower roller 5 provided with a driving disk 5e, the disks being disposed adjacent but of such diameter that their peripheries normally do not contact, same being 40 slightly spaced apart.

The driving disk 5e is of such diameter that it will not make a complete revolution while the bed travels through its stroke limits, and in the periphery of driving disk 5e are a pair of recesses 5g in which are arranged radially movable friction driving blocks 5f, said blocks being of substantial arcuate length and being normally urged outwardly by springs 5h, suitable means being provided to retain the blocks in the recesses. Blocks 5f are so spaced that when the bed 4 approaches either outer extremity of its movement, as in Fig. 2, a block 5f will pass into frictional contact with the periphery of driven disk 6e, so that when the bed reaches its extreme limit of movement the blocks 5f will exert frictional pressure on the driven disk 6e for substantially the full arcuate length of the block when the movement of the bed is reversed, the block 5f thus serving to overcome the inertia of upper roller 6 50 as the bed starts its reverse stroke in the direction of the arrow (Fig. 2), and causing the upper roller 6 to rotate in the same direction as the movement of the bed. As soon however as block 5f passes out of contact with driven disk 6e the drive for upper roller 6 will be released, allowing said roller to revolve freely over the type form and blanket on the bed, same being driven only by the frictional contact of its surface with the blanket (not shown) on said type form while 55 the form is passing under roller 6 on the matrix

rolling stroke. As the bed may pass to either side of upper roller 6 when rolling a matrix, on either or both strokes of the bed, two such friction blocks 5f are provided in driving disk 5e so spaced as to drive positively the upper roller as above described at each extremity of the bed's stroke. As the lower roller 5 does not make a complete revolution in rolling a matrix, there is ample space on the driving disk 5e for positioning the two friction blocks 5f. In the construction shown 10 in Figs. 1-3 the driving and driven disks 5e, 6e are housed entirely within the side frame 2 of the machine, as were the intermeshing gears in the aforesaid application which the said disks replace.

15 In Fig. 4 a mat rolling machine is shown which is actuated by a worm gear drive. In this modification the shaft for the lower roller 5 is provided with a large worm gear 5x meshing with a worm 10 on a shaft 11 which may be driven directly by a motor 12. The shaft of the lower roller is also provided with pinions 5d meshing with racks 4d (not shown) on the underside of the bed 4 as in Figs. 1-3. In this modification the shafts of both the upper and lower rollers extend through the frame 2x, and the shaft of the upper roller is provided with the driven disk 6e as in Figs. 1-3, while the shaft of the lower roller is provided with a driving disk 5e as in Figs. 1-3, the disk 5e carrying the two friction blocks 5f adapted to contact with the driven disk 6e when the bed 4 is in either outer extremity of its movement. In Fig. 4 the disks 6e and 5e are disposed outside the frame 2x.

20 The friction blocks 5f may be of any desired 30 form. They may be raised friction surfaces, or formed and mounted as shown in Figs. 1 and 2, or may be formed and mounted as shown in Figs. 5 and 6. In Figs. 5 and 6 the disk 5e is provided with rectangular recesses 5k extending from side to side through the disk 5e at its periphery and the friction blocks 5f conform in shape to the recesses and are provided with arcuate outer faces. Radially disposed bores 5m are provided in the blocks 5f, the inner ends of which are 35 reduced as at 5n, and studs 5o are passed through the bores 5m with their heads disposed within the larger ends 5m of the bores, the studs passing through enlarged bores 5p in the bases of the recesses 5k, the studs 5o having reduced lower 40 ends 5q which are threaded into tapped bores 5r at the bases of bores 5p. Studs 5o are of sufficient length so that the friction blocks 5f may move radially thereon with respect to disk 5e, the blocks being normally urged outwardly on the 45 studs, until the heads of the studs seat in the bases of bores 5m, by means of coiled springs 5s around the studs within bores 5p having their ends respectively engaging the undersides of blocks 5f and the bottoms of bores 5p. The blocks 5f are thus yieldably mounted on the disk 5e 50 while maintained in proper positions thereon.

55 I do not limit my invention to the exact forms shown in the drawings for obviously changes may be made therein within the scope of the 60 claims.

65 I claim:—

1. In a matrix rolling machine, a frame; a bed reciprocably mounted in the frame; a roller journaled in the frame above the bed; a shaft 70 journaled in the frame and disposed parallel with the roller; means for synchronously driving the bed and shaft; and normally disengaged means on the roller and shaft adapted to engage when the bed is at and adjacent its extreme outward 75

- limits of movement to cause the roller to rotate synchronously with the bed.
2. In a matrix rolling machine as set forth in claim 1, said engaging means being housed within 5 the frame of the machine.
3. In a matrix rolling machine as set forth in claim 1, said engaging means comprising a disk on the roller; a member on the shaft normally disengaged from the disk; and friction elements 10 on the member so disposed that an element will contact the disk whenever the bed is at and adjacent said limits.
4. In a matrix rolling machine as set forth in claim 1; said engaging means comprising a driven 15 disk on the roller; a driving disk operated by the shaft adjacent and normally spaced from the driven disk and adapted to make less than one complete revolution while the bed is moving between said limits; and a pair of friction elements 20 mounted on the driving disk so disposed that one element will contact the driven disk whenever the bed is at and adjacent said limits.
5. In a matrix rolling machine as set forth in claim 1; said engaging means comprising a driven 25 disk on the roller; a driving disk on the shaft opposite and normally spaced from the driven disk and adapted to make less than one complete revolution while the bed is moving between said limits; and a pair of friction blocks 30 of substantial arcuate length yieldably mounted in the periphery of the driving disk and so disposed that one block will contact the driven disk whenever the bed is at and adjacent said limits.
6. In a matrix rolling machine, a frame; a bed reciprocably mounted in the frame; an upper roller journaled in the frame above the bed; a lower roller journaled in the frame below and supporting the bed and disposed parallel with the upper roller; means for synchronously driving 35 the bed and lower roller; and normally disengaged means on the rollers adapted to engage when the bed is at and adjacent its extreme outward limits of movement to cause the upper roller to rotate synchronously with the bed.
7. In a matrix rolling machine as set forth in claim 6, said engaging means being housed within 40 the frame of the machine.
8. In a matrix rolling machine as set forth in claim 6; said engaging means comprising a disk on the upper roller, a member on the lower roller normally spaced from the driven disk; and friction elements 45 on the member so disposed that an element will contact the driven disk whenever the bed is in and adjacent said limits.
9. In a matrix rolling machine as set forth in claim 6; said engaging means comprising a driven disk on the upper roller, a driving disk operated by the lower roller adjacent and normally spaced from the driven disk and adapted 50 to make less than one complete revolution while the bed is moving between said limits; and a pair of friction elements mounted on the driving disk so disposed that one element will contact the driven disk whenever the bed is at and adjacent said limits.
10. In a matrix rolling machine as set forth in claim 6; said engaging means comprising a driven disk on the upper roller, a driving disk

on the lower roller opposite and normally spaced from the driven disk and adapted to make less than one complete revolution while the bed is moving between said limits; and a pair of friction blocks of substantial arcuate length yieldably mounted in the periphery of the driving disk and so disposed that one block will contact the driven disk whenever the bed is at and adjacent said limits.

11. In a matrix rolling machine having a reciprocable bed, and having a roller coacting with the bed, and having a shaft parallel with the roller, and having means for synchronously driving the bed and shaft; a driven disk on the roller; a driving disk on the shaft normally disengaged from the driven disk; and members on the driving disk adapted to contact the driven disk whenever the bed is at and adjacent its extreme outward limits of movement to the roller to revolve synchronously with the bed while the members are in said contact.

12. In a matrix rolling machine as set forth in claim 11, said driving disk making less than one complete revolution while the bed is moving between said limits.

13. In a matrix rolling machine as set forth in claim 11, said members comprising friction blocks of substantially arcuate length radially movably mounted in recesses in the periphery of the driving disk; and spring means for normally urging the blocks outwardly.

14. In a matrix rolling machine having a reciprocable bed, and having an upper roller coacting with the bed, and having a lower roller supporting the bed and disposed parallel with the upper roller, and having means for synchronously driving the bed and lower roller; a driven disk on the upper roller; a driving disk on the lower roller normally disengaged from the driven disk; and members on the driving disk adapted to contact the driven disk whenever the bed is at and adjacent its extreme outward limits of movement to cause the upper roller to revolve synchronously with the bed while the members are in said contact.

15. In a matrix rolling machine as set forth in claim 14, said driving disk making less than one complete revolution while the bed is moving between said limits.

16. In a matrix rolling machine as set forth in claim 14, said members comprising friction blocks of substantially arcuate length radially movably mounted in recesses in the periphery of the driving disk; and spring means for normally urging the blocks outwardly.

17. In a matrix rolling machine having a reciprocable bed adapted to receive a type form, flong, and blanket, and having a roller for exerting pressure on the blanket, and having means for reciprocating the bed; means actuated by the bed whenever the bed is at and adjacent its extreme outward limits of movement for causing the roller to revolve synchronously with the bed until the blanket enters the bite of the roller, the roller being rotated by frictional contact with the blanket during the remaining portions of each stroke.

HERBERT C. BEHRENS.
